UNITED STATES PATENT OFFICE.

FERDINAND HOLBERG, OF NEW YORK, N. Y.

PIPE.

SPECIFICATION forming part of Letters Patent No. 621,918, dated March 28, 1899.

Application filed August 3, 1895. Serial No. 558,114. (No model.)

To all whom it may concern:

Be it known that I, FERDINAND HOLBERG, a citizen of the United States, and a resident of New York, in the county of New York and 5 State of New York, have invented certain new and useful Improvements in Pipes, of which the following is a specification, reference being had to the accompanying drawings, forming a part thereof, in which similar letters of reference indicate corresponding parts.

This invention relates to pipes; and the object thereof is to provide an improvement in this class of devices by means of which the pipe may be cleaned and the stem thereof 15 cleansed of any impurities that may collect therein at any time; and with this and other objects in view the invention consists in the construction, combination, and arrangement of parts hereinafter described and claimed.

20 The invention is fully disclosed in the following specification, of which the accompanying drawings form a part, in which—

Figure 1 is a central longitudinal section of a pipe and the stem thereof provided with 25 my improvement, and Figs. 2 and 3 represent details of the construction.

In the practice of my invention I employ an ordinary pipe, the central bore B of the stem of which communicates with the bowl C at 30 the bottom thereof, which is preferably concaved, as shown in Fig. 1, and the central bore B of the stem of the pipe extends a short distance past the opening D in the bottom of the bowl, which communicates therewith.

35 Within the outer end of the stem is a screw-threaded tube or sleeve E, which is provided with a screw-threaded extension with which the mouthpiece F is connected, and the inner end of the screw-threaded tube or sleeve 40 E is provided with cross-bars, which are in the form of a wheel, as shown at G, Fig. 3, with which central portion of said wheel is connected a rod H, which extends inwardly past the opening in the bottom of the bowl of the pipe and is provided with a disk K.

The tube or sleeve E may or may not be provided with a shoulder or flange L, against

which the mouthpiece abuts. If this shoulder or flange is not provided, however, the mouthpiece will abut against the end of the 50 stem B, as will be readily understood. By means of this construction any dirt or substance of any kind which may pass from the bowl of the pipe into the stem may be readily removed therefrom by removing the mouthpiece within the tube or sleeve E and drawing out the rod H, with the piston K at the inner end thereof, and it will readily be seen that by reason of this construction any nicotine or fluids from the mouth that my collect 60 within the stem of the pipe may also be removed therefrom, and the stem may be thoroughly cleansed by removing the tube E, with the rod H and the disk thereon, as hereinbefore described.

65 It will thus be seen that I accomplish the object of my invention by means of a device simple in construction and operation and which is comparatively inexpensive.

Having fully described my invention, I 70 claim and desire to secure by Letters Patent—

A pipe provided with a stem having an enlarged bore extending beyond the opening in the bottom of the bowl of the pipe, an exteriorly-screw-threaded sleeve having screw-threaded connection with the extremity of 75 said stem, said sleeve having an interior web or spider with a central opening, a rod provided with a disk adapted to rest in the extremity of said bore beyond said opening, the 80 other end of said rod being secured in the opening in said spider and a mouthpiece secured on said sleeve, whereby when said sleeve is disconnected and withdrawn said disk will be drawn through said bore to clean the same, 85 substantially as described.

In testimony that I claim the foregoing as my invention I have signed my name, in presence of two witnesses, this 25th day of July, 1895.

FERDINAND HOLBERG.
